SUCTION CLEANER

Rudolph Kahn, New York, N. Y.

Application April 25, 1939, Serial No. 269,835

2 Claims. (Cl. 15—269)

This invention relates to suction cleaners, and more particularly to such cleaners of the so-called "cylinder" type.

In recent years there has been a great increase in popularity of suction cleaners of the "cylinder" type, that is, cleaners in which the cloth dust bag is housed within a cylinder which is left in stationary position in a room while the brush or nozzle or other tool is manipulated about the room, it being connected to one end of the cylinder by a suitable, flexible hose. The motor and fan are located at the opposite end of the cylinder which may, for convenience, be called the "motor end." The cylinder rests on runners and is provided with a handle for moving the same from room to room.

The primary object of my invention is to facilitate emptying of the dust bag used in such a cleaner, and more particular objects are to avoid excessive escape of dust, and to expel even clumps or clots of nap without having to dirty one's hands by handling the same.

In accordance with features and objects of the present invention, I provide a supply of discardable paper sacks which are suitably dimensioned to be received in the shell or cylinder of the machine. These are preferably provided with a stiffening or reinforcing ring at the mouth. To empty the regular porous dust bag of the cleaner, the cleaner is first stood upright on its motor end, and the cap is then removed from the upper end. The paper sack is inverted to bring its mouth against the mouth of the cloth bag, whereupon the cloth bag is lifted from the cylinder and the assembly inverted to bring the paper sack bottom-most, following which the paper sack is inserted in the cylinder. The rings of the cloth bag and paper sack are clamped in position by means of the regular clamps on the cylinder. The contents of the cloth bag are then discharged into the paper bag by slightly shaking the cloth bag, and more importantly, by pushing the cloth bag toward and even into the paper sack, for this "push emptying" readily transfers clots or lumps of material from the bag into the sack. It will be observed that a most important feature of this procedure is that the regular shell or cylinder of the cleaner acts as a supporting means for the paper sack during the transfer of dirt to the paper sack.

To the accomplishment of the foregoing, and such other objects as will hereinafter appear, my invention consists in the discardable dust sack and the cylinder type suction cleaner elements and their relation one to the other, as herein-

after are more particularly described in the specification and sought to be defined in the claims.

The specification is accompanied by drawing, in which:

Fig. 1 is a partially sectioned side elevation of a typical cylinder type suction cleaner;

Fig. 2 is a partially sectioned side elevation showing the same in upright position during removal of the dust bag;

Fig. 3 is a similar section showing the manner in which the discardable paper sack is supported by the cylinder during the transfer of dirt from the dust bag to the sack;

Fig. 4 illustrates the construction of the paper sack; and

Fig. 5 shows the sack in folded condition.

Referring to the drawing, and more particularly to Fig. 1, the suction cleaner is of the so-called cylinder type, it comprising a cylindrical shell or housing 12 carrying a porous fabric dust bag 14. Various tools or accessories, such as the brush 16, may be detachably connected to a stiff tube or pipe 18, and this in turn is connected to a flexible hose 20, leading to one end of cylinder 12. The opposite end of the cylinder is the motor end, and carries an electric motor and fan. The motor is supplied with current through a flexible cord 22 plugged into the cleaner at 24, and the operation of the motor may be controlled by a conventional switch 26. The cylinder rests on suitable supports, which ordinarily take the form of skids or runners 28. A handle 30 is provided to facilitate carrying the cleaner from room to room.

The hose is connected to a cap or closure 32, and this is detachably clamped in position by appropriate clamps 34. The mouth of the dust bag 14 is sealed between the cap 32 and the end of the cylinder. Referring to Fig. 2, it will be seen that dust bag 14 is secured to a metal ring 36, this ring being outwardly flanged and ordinarily being provided with a suitable rubber covering or gasket 38. The flange of the ring is dimensioned to fit against a mating ledge or seat 40 permanently secured to the open end of cylinder 12.

In accordance with the present invention, I provide a paper sack which is inexpensive and may be discarded with the dirt from the cleaner. The paper sack may assume a variety of forms, and one preferred form is that illustrated in Fig. 4, in which a paper sack 42 is provided with a cardboard ring 44 to which the paper sack is cemented or otherwise secured. The sack 42 is dimensioned to be

received within the cylinder 12, as will be seen from inspection of Fig. 3. The ring 44 at the end of the paper sack is preferably dimensioned the same as the ring 36 at the mouth of dust bag 14. The ring 44 is thereby adapted to rest upon the seat 40, as shown in Fig. 3; thus, supporting the paper sack within the cylinder much as the cloth bag is normally supported. This is a great convenience in order to hold the paper sack during the transfer of dirt from the cloth bag into the paper sack.

The procedure followed will be self-evident from examination of the drawing. The cleaner is first stood upright on its motor end, following which the clamps 34 are released and the cap or closure 32 is removed. The motor end of the cleaner is ordinarily made flat, as is indicated at 46, in order to facilitate standing the cylinder on end. In fact, this procedure as so far described has been followed heretofore, but in accordance with prior practice, the cloth dust bag 14 is removed and inverted over a newspaper, garbage pail, or the like, to empty its contents. Much dust flies around during the emptying operation, and further difficulty is frequently caused by a tendency of the dirt to clot or lump up due to the fibrous nature of the nap drawn into the cleaner from carpets.

In accordance with the present invention, the paper sack 42 is inverted over the dust bag 14 before the dust bag is removed from the cleaner. The ring 44 of the sack is held against the ring 36 of the dust bag as the latter is removed from the cleaner. Fig. 2 illustrates the assembly of bag and sack during their upward movement. The assembly is then inverted while holding the rings together, thus bringing the paper sack to the bottom. The paper sack is then inserted in the cylinder as shown in Fig. 3, and the parts are held together by closing of the clamps 34. If desired, an extra metal ring may be provided which is to be slipped over the dust bag before closing the clamps 34, the clamps then holding the ring, which in turn holds the bags together. No such ring is here illustrated, and it will be understood that in many cases the ring is unnecessary, for the thickness of the cap or closure 32 at the clamp is replaced by the thickness of the ring 44 of the sack. If, however, in a special case the cap or closure 32 is of such configuration and cooperates in such fashion with the clamps that the clamps would be ineffective if used directly on the ring of the cloth bag, then a special ring may be provided resembling the peripheral portion of the cap or closure 32. This special ring is cut away so largely at the middle that it readily slips over the dust bag 14. It then engages the ring of the dust bag and is in turn engaged by the hooks of the clamps 34.

It is obvious that with the parts in the relation shown in Fig. 3 a slight shaking of bag 14 will transfer much of the dust and dirt into the sack 42. However, shaking is not to be particularly

relied upon, and in itself tends to cause escape of dust. An important advantage of the present arrangement is that it makes possible what I term "push emptying" of the dust bag, for it is merely necessary to depress the bag downwardly, as is indicated in broken lines, thereby actually pushing the dirt, and particularly the large lumps or clots of nap, into the paper sack 42.

When the bag has been satisfactorily emptied the clamps 34 are released and the sack is removed from the cylinder and discarded with its contents. The bag 14 is then replaced, following which the cap or closure 32 is applied thereover and the clamps 34 are again locked, whereupon the cleaner is ready for use.

The paper sack 42 may be suitably creased for folding the same into flat condition. One method of folding is shown in Fig. 5, and in this figure the folds have been left slightly open to better indicate the manner in which the sack has been folded. Other methods of folding may also be adopted.

It is believed that the construction and operation, as well as the many advantages of my improvement will be apparent from the foregoing detailed description thereof. It will also be apparent that while I have shown and described my invention in a preferred form, many changes and modifications may be made without departing from the spirit of the invention defined in the following claims.

I claim:

1. The method of emptying the porous dust bag of a horizontal cylinder type suction cleaner which includes standing the cleaner upright, removing the cap at the upper end, inverting a non-porous discardable sack to bring the mouth of the sack against the mouth of the bag, removing the bag while holding the sack thereagainst, inverting the bag assembly and inserting the sack down into the cylinder of the cleaner, and then discharging the contents of the bag into the sack while the sack is supported and protected by the then upright cylinder.
2. The method of emptying the porous cloth dust bag of a horizontal cylinder type suction cleaner which includes standing the cleaner upright on its motor end, removing the cap at the upper end, inverting a non-porous paper bag to bring the mouth of the paper bag against the mouth of the cloth bag, removing the cloth bag while holding the paper bag thereagainst, inverting the bag assembly and inserting the paper bag down into the cylinder of the cleaner, clamping the ring of the cloth bag in position by means of the regular clamps on the cylinder, and then discharging the contents of the cloth bag into the paper bag, as by pushing the cloth bag into the mouth of the paper bag at the upper end of the cylinder, the paper bag being supported and protected during the transfer by means of the then upright cylinder.

RUDOLPH KAHN.
